UNITED STATES PATENT OFFICE.

ERNEST NAUER, OF CHICAGO, ILLINOIS.

GASEOUS-FLUID COMPRESSOR.

1,000,539.

Specification of Letters Patent. Patented Aug. 15, 1911.

Application filed October 24, 1910. Serial No. 588,736.

To all whom it may concern:

Be it known that I, ERNEST NAUER, a citizen of the United States, and a resident of the city of Chicago, county of Cook, and 5 State of Illinois, have invented certain new and useful Improvements in Gaseous-Fluid Compressors, of which the following is a specification.

My invention relates to gaseous-fluid compressors and more specifically to that class thereof involving the employment of revolute cylinders.

10 The object of my invention is the provision of a compressor of the character mentioned which will be of durable and economical construction and efficient in operation.

Other objects will appear hereinafter.

With these objects in view my invention consists in a gaseous-fluid compressor characterized as above mentioned and in certain details of construction and arrangements of parts all as will be hereinafter more fully described and particularly pointed out in the appended claims.

25 My invention will be more readily understood by reference to the accompanying drawings forming a part of this specification and in which,

Figure 1 is a central section of a compressor embodying the preferred form of my invention, being a slight enlargement of a section taken on substantially line $x-x$ of Fig. 3 with the cylinders and pistons turned to the position shown by dotted lines 30 in said figure, Fig. 2 is a transverse sectional detail of the inner end portion of the cylinders and the parts communicating therewith, showing said cylinders in the dotted line position in Fig. 3, and Fig. 3 is a transverse section slightly reduced taken on substantially line $y-y$ of Fig. 1.

The preferred form of my invention as illustrated in the drawings comprises a circular casing or shell 1 which is formed preferably integral with a base 2 so that in operation said casing will be held stationary. Also formed integral with said base 2 is an upwardly extending bearing bracket 3. One side of the casing 1 is open, the same 45 being closed by a head 4 which is tightly secured thereto by means of screws 5. Extending eccentrically through the casing 1 is a horizontal shaft 6, one end of the latter being mounted in the head 4 and fitted thereinto by a key 7, the opposite end of said shaft 55 being supported in the bracket 3 whereto

the same is also secured against rotation by means of a set screw 8. Upon the first mentioned end of said shaft is threaded a collar 9 which rests against the outer end of the bearing portion of the head 4, said collar being provided in order to prevent longitudinal movement of said shaft in one direction relative to the casing 1. A set screw 10 threaded through the collar 9 serves as a means of locking the latter in any position of adjustment upon said shaft.

Arranged within the casing 1, the same being rotatably mounted upon the shaft 6 is a circular cylinder-member 11 said member 70 11 is formed with an elongated bearing portion or hub 12 which projects through the stationary head of the casing 1, a suitable packing 13 interposed between said head and hub serving an obvious purpose. The hub 75 12 is, as seen, of a sectional nature, the inner or bearing portion 14 thereof which engages the shaft 6 being adapted to be detached so that when the same becomes worn it may be readily renewed or replaced at a very small 80 expense. Set screws 15 serve to hold said portion 14 in operative position and for rigidly securing the same to the body of the hub 12. With the arrangement disclosed it will be seen that in order to remove the 85 member 14 it is only required to loosen the screws 15, since by so doing said portion 14 may be slid longitudinally from engagement with said hub and from its position upon the shaft 6 after removal of the latter from its 90 bearings. A collar 16 threaded upon the shaft 6 adjacent the extremity of the hub 12 serves to maintain a constantly longitudinal release between said hub and shaft, a set screw 17 threaded into said nut serving to 95 lock the same in any position of adjustment. Oil ducts 18 communicating with suitable oil cups 19 extended, as will be observed, to the various bearings serves to effect lubrication thereof when the device is in operation.

100 Fixed upon the exteriorly projecting end portion of the hub 12 is a fly-wheel 20. Formed in the cylinder-member 11 is a plurality of equally spaced radial projecting cylinders 21 preferably four in number as shown. Reciprocally mounted in the cylinders 21 are pistons 22 the outer extremities of which project beyond the periphery of said cylinders. Formed in the outer extremities of the pistons 22 are transversely 105 extending channels 23 in which are mounted rollers 23', said rollers being free for rotary 110

movement in said piston ends but held therein against movement longitudinally of said pistons.

Arranged within the casing 1 upon the inner sides of the respective heads thereof adjacent the peripheries of said heads are annular hardened metal members 24, the latter being rigidly secured in position by means of dowel pins 25. Said annular members 24 together with a hardened metal ring or strip 26 arranged upon the inner side of the peripheral wall of the casing 1 form annular cam grooves eccentric with the axis of the shaft 6 and hence the cylinder-member 11. Said cam grooves are engaged by the respective extremities of the rollers 23' so that when the cylinder-member 11 and hence the pistons 22 are revolved reciprocatory movement relative to the cylinders 21 will be imparted to the pistons 22 due to the eccentricity of said cam grooves. The opposite sides of the pistons 22 adjacent the rings 24 are cut away as at 27 forming parallel flat sides which, when said pistons are revolved pass in close proximity with adjacent edges of said members 24. This provision serves to prevent relative rotary movement of said pistons serving to maintain the proper positioning of the rollers 23 relative to the cam grooves engaged thereby.

Formed in the shaft 6 is a longitudinally extending passage way 28 which communicates at its outer end with a gaseous-fluid supply pipe 29. The inner end portion of said passage way 28 terminates in an inlet port 28' positioned for communication with the inner ends of each of the cylinders 21 when the cylinder-member 11 is rotated. Also formed through the shaft 6 is a longitudinally extending passage way 30 the outer extremity of which communicates with a discharge or exhaust pipe 31. The inner end portion of said passage way 30 terminates in an exhaust port 30' which is also positioned for communication with each of the cylinders 21 as the cylinder-member 11 is rotated. Said ports are so arranged, as will be observed by reference especially to Figs. 2 and 3 that, with reference to each of the cylinders 21 that when the piston 22 carried thereby is at its inner terminal of movement said cylinder will be in communication with neither of said ports. Upon rotation of the member 11 in the direction shown by the arrow in Fig. 3 said cylinder will be brought to communicate with the port 28, remaining in communication with said port until the piston operating therein has reached its outer terminal of movement whereupon communication with the inner end of said cylinder will be discontinued thereby imprisoning the gaseous-fluid drawn therein while in communication with the port 18'. Said cylinder will remain closed through 90° of movement of

the cylinder-member 11 whereupon the same will be brought into communication with the exhaust port 30'. In this movement, however, of the member 11 the piston of said cylinder will be forced inwardly causing the compression of the gaseous-fluid imprisoned in said cylinder and so that when the latter is brought into communication with the port 30' as above mentioned the fluid discharged thereinto will be in a high state of compression as is desired. With the arrangement disclosed, it will be observed, that when the device is in operation, that is when the cylinder-member 11 is rotated each of the cylinders will be brought successively into communication first with the intake port 18' where gaseous-fluid will be supplied thereto and then to the discharge port 30' wherein fluid will be discharged in a state of compression.

In order to effect a tight connection between the cylinder-member 11 and the shaft 6 the portion of the latter contacting with said cylinder-member in the vicinity of the cylinders 21 is conically formed, said portion of said cylinder-member being correspondingly formed. With this arrangement upon any wear of said surfaces the shaft 6, through the medium of the threaded collars 9 and 16 may be moved longitudinally in its bearings to take up such wear.

The device as set forth is durable and economical, the same is of high efficiency in operation and is not susceptible to readily becoming inoperative.

While I have shown what I deem to be the preferred form of my invention, I do not wish to be limited thereto as there might be various changes made in the details of construction and arrangements of parts described without departing from the spirit of my invention, and hence I desire to avail myself of such changes and alterations as fairly fall within the scope of the appended claims.

Having described my invention what I deem as new and desire to secure by Letters Patent is:

1. In a compressor, the combination of a circular casing; a plurality of cylinders in said casing revolving in unison about a common axis eccentric with the axis of said casing; pistons mounted for reciprocation within said cylinders; a hardened metal lining ring arranged upon the inner side of the peripheral wall of said casing; hardened metal shoulder rings secured to the inner sides of said casing and, in conjunction with said lining ring, forming cam grooves; rollers at the outer ends of said pistons engaging said cam grooves; and intake and exhaust ports arranged for communication with the inner ends of said cylinders, each of said cylinders being adapted upon rotation to be successively brought

into communication with said ports, substantially as described.

2. In a compressor, the combination of a circular casing; a plurality of cylinders in 5 said casing revolving in unison about a common axis eccentric with the axis of said casing; pistons mounted for reciprocation within said cylinders; a hardened metal lining ring arranged upon the inner side of the 10 peripheral wall of said casing; hardened metal shoulder rings secured to the inner sides of said casing and, in conjunction with the said lining ring, forming cam grooves, the sides of said pistons being flattened and 15 bearing against the inner side faces of said

shoulder rings; rollers at the outer ends of said pistons engaging said cam grooves; and intake and exhaust ports arranged for communication with the inner ends of said cylinders, each of said cylinders being 20 adapted upon rotation to be successively brought into communication with said ports, substantially as described.

In testimony whereof I have signed my name to this specification in the presence of 25 two subscribing witnesses.

ERNEST NAUER.
